[57] **CLAIM**

The ornamental design for a drain unit for collecting and removing water from vehicle tires, as shown.

DESCRIPTION

FIG. 1 is a perspective view of a drain unit for collecting and removing water from vehicle tires showing my new design;

FIG. 2 is a side elevational view thereof, the side opposite being a mirror image of the side shown in FIG. 2;

FIG. 3 is an end elevational view thereof;

FIG. 4 is an opposite end elevational view thereof;

FIG. 5 is a top plan view thereof; and,

FIG. 6 is a bottom plan view thereof.

FIG. 1.

FIG. 2.

FIG. 5.

FIG. 3.

FIG. 6.

FIG. 4.
